7 Claims

ABSTRACT OF THE DISCLOSURE

A lamp socket is held securely against turning in a lamp casing in order to hold in proper position the filaments of a bulb in said socket. The means holding the socket in the casing are of a resilient nature, so as to permit flexing of the holding means and absorption of shock to prevent damage to the lamp, while yet effectively holding the socket against rotation.

This invention relates to the mounting of a lamp bulb socket in an automobile lamp so that the lamp bulb may be held in an effective accurate position relatively to the horizontal and vertical. In automobile lamps, it is absolutely essential that those lamp bulbs having high beam and low beam filaments, be particularly positioned at all times. Even a slight inaccuracy of location, such as a rotation of a few degrees will throw the beams generated by the filaments into improper position.

It is naturally possible to locate lamp bulb sockets accurately, through use of rigid and relatively costly assembly means. These means are subject to erosion and wear, as well as shock, and simply are not effective. It is the purpose of my invention to contribute accurate and effective means which will withstand wear and which will absorb shock, and yet function with the accuracy required.

As those skilled in the art will appreciate, severe shock applied to an automobile, as when its bumper encounters a fixed obstruction, will cause severe damage to a bulb filament. If rigid means are utilized to hold a socket in position, it is obvious that it will be impossible to have effective shock absorbing means. As a feature of my invention, I contribute shock absorbing means for effectively holding against rotation a lamp bulb socket.

Further, it is a feature of my invention that the lamp bulb socket is held against movement in all directions, even though yielding means are utilized. Even further, the yielding means are not subject to wear, and will not lose their effectiveness or accuracy.

Also, as will be made apparent, the assembly mechanism through which the lamp bulb socket is held effectively in a particular position, is extremely simple and inexpensive, and utilizes a minimum number of parts, easily assembled for the purpose required.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention.

Referring now to the drawings, FIG. 1 is an elevation looking into the open end of a lamp casing from the direction of the arrow 10 in FIG. 3. FIG. 2 is an elevation of the lamp casing taken when looking at FIG. 3 in the direction of the arrow 11. FIG. 3 is a section taken along

2

line 3—3 of FIG. 1. FIG. 4 is an exploded view of the several parts of my invention shown assembled in FIG. 3.

The lamp casing to which my invention is applied is designated generally by reference numeral 15. This casing is tapered, but the shape is of no real importance, since

5 the invention resides particularly in the assembly showing in FIG. 3 utilizing the base plate of the lamp casing designated by reference numeral 16. The base plate is preferably formed of a plastic material having a central opening 17, and a pair of integral pins 18 at opposed sides of the opening. Preferably, the opening 17 and the pins 18 are formed in an offset portion of the base 16, as best seen in FIG. 3, the offset portion being there designated by numeral 19.

10 15 An insulated resilient washer 20 is formed with an opening 25 adapted for alignment with the opening 17 of the offset base plate portion 19. The washer 20 is also formed with a pair of upstanding lugs 21, each of which is grooved or slotted at 22 so that when the washer 20 is applied to the base plate, interlocking takes place between the pins 18 and the slots or grooves 22 of the upstanding lugs 21. It is obvious that the resilient washer 20 will be locked against rotation relatively to the base plate 16.

20 25 A metal member which may take the form of a washer, is designated by reference numeral 23, and is adapted to be applied against the resilient washer 20, washer 23 being formed with an opening 24 for alignment with openings 17 and 25. Washer 23 is formed with slots or grooves 26 adapted to fit over the lugs 21 and thereby to lock the washer 23 against rotation relatively to resilient washer 20 and the base plate 16. It will be noted that while the washer 23 is formed of metal and is therefore rigid, it will be held yieldingly against rotation by resilient lugs 21 of the resilient washer 20.

30 35 The lamp socket of my invention is designated by reference numeral 30, and it is formed with a usual type of compound slot 31 for the entry of a pin 32 formed on the ferrule 33 of a lamp bulb L. This is naturally standard construction. The socket 30 is formed with a pair of opposed grooves or slots 35 that are adapted to coact with lugs 36 integral with the washer 23 and extending into the opening 24 of that washer. When the socket 30 is moved into the opening 24 toward its final position of FIG. 3, 40 45 grooves 35 coact with the lugs 36 of washer 23 and obviously prevent rotation of the socket 30 relatively to the remaining parts, and particularly the base 16. Also, the lugs 36 will ride into grooves 35 until they encounter end surfaces 37 of the grooves whereupon further movement 50 inwardly of the washer 23 by socket 30 will be prevented.

55 60 As is clearly shown in FIG. 3, a portion of the resilient washer 20 extends into the opening 17 of the base 15 when the washer 20 is applied to the two pins 18. It will be also seen in FIG. 3 that a second resilient washer at the back or outside of the casing, fits against the outer surface of the offset portion 19 of base plate 16. This washer is designated by reference numeral 40 and is formed of the same material as the washer 20. A portion thereof enters also the opening 17 and fits against 65 70 that part of the washer 20 lying within the said opening. Between the two washers, the socket 30 is insulated from the base plate 16.

75 80 It will be noted from FIG. 3 that the movement of the socket 30 into the opening 24 of the washer 23, the aligned opening 25 of the washer 20, the opening 17 of the base plate 15, and then an opening 44 of the washer 40, will be limited by the lugs 36 of the metal washer 23 coacting with the end surfaces 37 of grooves 35. A further metal washer 45 may now be applied about the end 85 of the socket 30 protruding outwardly of the casing, and against resilient washer 40. Now, by a simple spinning over of the end of the socket 30, that socket is secured

within the openings of the base plate and the several washers as well illustrated in FIG. 3.

It is further obvious that while the socket 30 will be held firmly against rotation or endwise movement relatively to base plate 16, it will nevertheless be protected fully by resilient washers 40 and 20 against vibration and shock. Therefore, it can be said that I contribute a means for holding a lamp bulb in a particular desired rotated position with its filaments particularly aligned as desired, while yet protecting the lamp bulb against vibration.

In FIG. 1 the elements designated by reference numerals 50 and 51 are the contacts to which the light bulb is related when inserted into the socket 30. Further reference numeral 52 refers to a contact strip that extends to a fastening member 53 for the purpose of forming a ground. The two contacts 50 and 51 are necessary because two filaments are used in the light bulb. In FIG. 2, numerals 54 and 55 refer to conductors that are utilized for the lamp bulb.

I now claim:

1. In a lamp assembly, a base having an opening, an insulated yielding washer having an opening therethrough aligned with said opening in said base, interlocking means integral with said base and washer for locking said washer against sliding movement relatively to said base and rendered effective by the placing of one side of said washer against said base with said openings aligned, a metal washer having also an opening therethrough for alignment with said first openings applied against the other side of said yielding washer, interlocking means between said metal washer and yielding washer rendered effective by the placing of said metal washer against said yielding washer for locking said metal washer against sliding relatively to said yielding washer, a tubular lamp bulb socket adapted to traverse all of said openings, means between said tubular socket and metal washer for preventing rotation of said tubular socket relatively to said metal washer and therefore said base, and for limiting inward movement of said socket into said openings, a part of said socket extending through the opening of said base to lie beyond the said opening, and means co-operable with the said extending socket part locking said socket against movement outwardly from said base opening.

2. In the combination of claim 1, the feature that said means between said socket and metal washer comprise a lug on the metal washer and a slot in said socket.

3. In the combination of claim 1, the feature that said yielding washer and base interlock to hold said yielding washer against rotation on said base and that said metal washer when applied to said yielding washer then locks the metal washer and socket against rotation relatively to said base, and said means co-operable with said extending socket part being yielding and pressing said socket yield-

ingly against said metal washer to hold it and said yielding washer pressed against said base.

4. In the combination of claim 1, the feature that said means co-operable with said extending socket portion include a second yielding insulating washer lying against the base and having an opening traversed by said socket.

5. In the combination of claim 3, the feature that said second yielding insulating washer and said first yielding insulating washer are brought into end to end contact through a portion of at least one of said washers lying within the opening in the base of said lamp casing.

6. In a lamp assembly, a base having an opening, an insulated yielding washer having an opening therethrough aligned with said opening in said base, interlocking means on said base and washer for locking said washer against rotation relatively to said base and rendered effective by the placing of one side of said washer against said base with said openings aligned, a lamp bulb socket assembly comprising a tubular lamp bulb receptacle and a laterally extending portion secured relatively to said tubular receptacle with said portion and receptacle locked against rotation relatively to one another, interlocking means between said portion and yielding washer rendered effectively by the placing of said portion against the other side of said yielding washer for locking said portion and tubular socket against rotation relatively to said yielding washer and therefore relatively to said base, a part of said tubular socket lying within said opening in said washer and base and extending beyond the said base opening, and means co-operable with the said extending socket part for locking said socket against outward movement from said base opening.

7. In the combination of claim 6, the feature that said means co-operable with said extending socket part include a second yielding insulating washer lying against the base and having an opening traversed by said socket.
